(57) **CLAIM**

The ornamental design for a heat sink, as shown and described.

DESCRIPTION

FIG. 1 is a front side elevation view.

FIG. 2 is a right side elevation view.

FIG. 3 is a top plan view.

FIG. 4 is a bottom plan view; and,

FIG. 5 is a perspective view.

The rear side elevation view is omitted because it appears the same way as the front side elevation view. Likewise, the left side elevation view is omitted because it appears the same way as the right side elevation view.

The broken line showing of the environment is for illustrative purpose only and forms no part of the claimed design.
